COMBINED DESK AND SEAT UNIT OR SIMILAR ARTICLE

Alvaro De La Riva Careaga, Gran Avenida 24,
Savana Grande, Caracas, Venezuela

Filed May 5, 1961, Ser. No. 65,037

Term of patent 3½ years

(Cl. D33—11)

FIG. 1

FIG. 2

FIG. 4

FIG. 1 is a perspective view of a combined desk and seat unit, showing my new design;

FIG. 2 is a plan view thereof;

FIG. 3 is a sectional view, taken on the line 3—3 of FIG. 2; and

FIG. 4 is an elevational view of the combined desk and seat unit.

I claim:

The ornamental design for a combined desk and seat unit or similar article, substantially as shown.
